UNITED STATES PATENT OFFICE.

THOMAS WILSON, OF HULL, ENGLAND.

VALVE-MOTION FOR ENGINES.

No. 853,139.

Specification of Letters Patent.

Patented May 7, 1907.

Application filed July 22, 1905. Serial No. 270,816.

To all whom it may concern:

Be it known that I, THOMAS WILSON, a subject of the King of England, residing at 375 Hawthorn avenue, Dairy Coates, Hull, in the county of York, England, have invented certain new and useful Improvements in Valve-Motions for Engines; and I do hereby declare the following to be a full, clear, and exact description of the invention, such as will enable others skilled in the art to which it appertains to make and use the same.

This invention relates to improvements in valve motions for engines, and has for its object the dividing of the opening and closing of the admittance ports by a valve or valves of the ordinary flat or piston type with one spindle rod between two sets of motions combined, which may be linked up and reversed either separately or in combination. By this arrangement as the valve or valves are linked up to a shorter travel or earlier cut off of the live steam or other motive fluid used a wider opening of the admittance ports may be maintained and the exhausts may be also retained to a later period of the piston stroke than is now the practice by the usual valve or link motions.

My said improvements consist essentially in a supplementary valve motion added to any of the already well-known link motions such as Joy, Stephenson, Gooch and other similar valve motions. And in order that my said invention may be better understood, I will now proceed to describe the same with reference to the drawing accompanying this specification in which:

Figure 1 shows my improvements applied to an engine fitted with Joy's link motion; Fig. 2 shows my improvements fitted in a slightly modified form to the same link motion; Fig. 3 shows my improvements fitted to Stephenson's link motion; Fig. 4 shows my improvements fitted to Gooch's link motion. Figs. 5 and 6 are details hereinafter referred to.

In the figures, which are partly diagrammatic for the sake of clearness, the same letters and numerals of reference are employed to denote the same parts in all the views; the parts most closely connected with my invention being shown in heavy lines.

Referring first to Fig. 1, in this figure the valve *a* is shown taking steam in the center and the exhausts are taking place at the outer edges thereof. The valve is shown with the main or ordinary reversing arm *b* in

the out of gear position. *c* and *d* are steam ports. The valve *a* controls these steam ports *c* and *d* and the exhaust ports *e* and *f*. *g* is the spindle of the slide valve *a*. Any suitable guide may be fixed at *h* to carry the weight of the combined motions if found desirable. *i* represents a double ended lever or its equivalent, such as an eccentric placed between the ordinary and auxiliary motions, the ends of this lever *i* may be made of suitable proportions to suit each of the motions according to the design of the engine. *j* represents the auxiliary slide valve rod which may be straight or with a distance piece at the end as shown in Fig. 5. *k* represents the auxiliary lifting link. *l* is the auxiliary radius link which in this instance is shown as a double bar link with pinions added in the center at each side of the link, let into each side or lugs of the bracket *m*, which bracket carries the double bar link, the center pinions of which are let therein at either side thereof or the bracket may have pinions which may be let into the double bar link at the center. *n* represents the motion support plate of a locomotive, to which the bracket *m* may be made secure or in marine or stationary engines it may be secured to the bed plate or any other suitable part of the engine. *o* represents the auxiliary motion eccentric rod, one end of which is made fast to the auxiliary sheave *p* by a strap while the other end is made fast to the end pinion either at the top or bottom of the double bar link *l*, which, in this instance is shown attached at the bottom pinions. Any other suitable link or connection may be used which is equivalent thereto, such for instance as the double radius link *q* shown at Fig. 4. *p* shows the auxiliary motion sheave set and made fast on the crank shaft at about a right angle to the crank pin *r*. It may be set either to lead or follow the crank pin *r*, as required. *s* represents the auxiliary motion reversing arm in full gear while the broken lines show where it and other parts of the auxiliary motion would be in the opposite full gear. *t* shows the ordinary valve rod one end of which is connected to the double ended lever *i* and the other end to the valve connecting levers *u*. This valve connecting lever *u* is the ordinary valve connecting lever. *v* shows the ordinary fulcrum rod and *w* the ordinary radial rod, one end of which may be made fast to the auxiliary weigh bar as shown. *x* shows the ordinary connecting rod. *y* represents

the ordinary connection between the connecting rod and the crank pin r . z shows the crank shaft. 1 represents the connection between the connecting rod and the piston rod crosshead. 2 are slipper blocks. 3 the ordinary slipper or guide of the slipper blocks 2. b , as before stated, represents reversing arm of the ordinary motion in out of gear position. This is reversed in the opposite direction to that assumed in Fig. 2 on account of the slide valve rod t being coupled to the double ended lever i below instead of above the rod g and slipper block 2 of the valve connecting levers u . In this particular instance it would be desirable to always keep the ordinary and auxiliary motions at the distances apart shown, one of them being in out of gear position while the other is in either of the other full gear positions. To accomplish this I use or combine any two sets of ordinary reversing wheel and screw gearing for combined motion, the ordinary motion may remain as is usual except that it would have a cog or bevel wheel secured at each end of the revolving screw barrel of two diameters, while for the auxiliary motion there may be used a similar set and as it is desirable to reverse them both by one reversing wheel in this instance, I place the auxiliary motion revolving barrel with thread for threaded screw in thrust bearings at the ends, with an outer sleeve feathered thereon between the bearings, to which sleeve is also made fast two cogs or bevel wheels of two different diameters at the ends of this sleeve, one of which is exactly the same size as the larger cog or bevel wheel on the screw barrel of the ordinary screw reversing gear and may be slid in and out of it as required, while at the other end there would be three smaller cog or bevel wheels, one on the sliding sleeve feathered on to the threaded barrel of the auxiliary reversing screw, the cogs of which may be slid in and out of the cogs of a second similar smaller sized cog or bevel wheel as required, which second wheel is always in communication with the smaller cog wheel or bevel gearing at this end of the screw barrel of the ordinary screw reversing gear and the whole may be so arranged side by side that when the sleeve on the auxiliary screw barrel is in mid position they are locked and held secure in this position being in communication with each other. When either of the gears is brought to the center position it can go no farther in the same direction until the sleeve carrying the cog or bevel gearing movable wheels has first been changed as the other gear would then be in full travel.

With the mechanism shown at Figs. 2, 3 and 4, the auxiliary reversing gear may in all cases, after being reversed, be run in full travel or if desired may be graded along with the ordinary reversing gear as before described, or both motions may be graded and

reversed singly by any of the well-known reversing gears.

Referring again to Fig. 2, this shows the ordinary Joy valve motion with the auxiliary valve motion attached thereto and the arrangement is similar to that shown at Fig. 1 with the exception that the slide valve rod t is coupled to the double ended lever i above instead of below the valve rod g and slipper block 2 of the valve connecting levers u . The piston in this instance, would be at the commencement of the stroke instead of at half stroke as in Fig. 1 the valve a would also be arranged to admit steam at the outer edges instead of at the center as in Fig. 1.

Referring now to Fig. 3 this shows the ordinary Stephenson motion having auxiliary valve motion added thereto as in Figs. 1 and 2. In this case the piston is at the commencement of the stroke as in Fig. 2 and the valve a arranged to admit steam at the outer edges. In this figure, 4 shows a guide which may be replaced by a swinging link carrying the die bolt 5 of the ordinary slide valve rod t which may be either straight, bent, inclined or jointed. 6 is the ordinary radius link, and 7 is the ordinary lifting link, while 5 is the ordinary die bolt connection to the ordinary radius link 6.

At Fig. 5 is shown in cross section the auxiliary slide valve rod j , broken lines show where a strengthening rod may be attached if necessary when the double ended lever is straight, but the double ended lever i may be inclined or bent, in which case j may be a straight rod.

Referring to Fig. 6, this shows a section drawn to an enlarged scale of solid joint at the double bar link end of the auxiliary slide valve rod j . It consists of a guide 8 telescoped or screwed into a guide 9 on the double bar link l and connected to the auxiliary slide valve rod j before being made secure in the double bar link l . This joint may be used for any ordinary double bar gears. 10 is a motion bar or bars. The guide 8 may be bored out hollow as also may the center pinions of the double bar link l or its bracket m so that in the event of anything going wrong with the auxiliary motion sheave p or the auxiliary eccentric rod o an extra bolt carried on the engine for this purpose can be inserted.

Referring to Fig. 4, this shows the ordinary Gooch link motion with my auxiliary valve motion fitted thereto where there is only room for four eccentrics between the cranks, or for other classes of engines. In this figure, the parts are shown with steam being admitted from the center as in Fig. 1 and exhausting at the end of the piston valve a , ordinary flat valves being preferably employed. The piston is at the commencement of its stroke as in Figs. 2 and 3. In this figure, 11 is the foreway sheave and 12 is the backway sheave. 13 is the auxiliary

slot of the double radius link *q*, wherein slides the die bolt 14 of the auxiliary slide valve rod *j*, while 15 denotes the carrying links of the double combined radius slotted links *q*, which are shown suspended from the weigh bar of the reversing arm *b*.

The auxiliary slide valve rod *j* and the auxiliary eccentric rod *o* may form one rod in engines designed to run in one direction only or in non-reversible engines. In this instance I may find it convenient to dispense with the auxiliary double bar radius link *l*, the bracket *m*, auxiliary reverse gear *s* and the auxiliary lifting link *k*.

15 What I claim and desire to secure by Letters Patent of the United States of America is:—

1. In a valve motion, the combination of a valve and its stem, an operating lever pivoted to said stem, a main link motion pivoted to said lever, an auxiliary link motion connected to the other end of said lever, and means for reversing said motions separately, substantially as described.

25 2. In a valve motion, the combination of a valve and its stem, an operating lever connected to said stem, a main link motion pivoted to one end of said lever, an auxiliary

link motion pivoted to the other end of said lever, including an eccentric, a rod operated by said eccentric, a link operated by said rod, and connections between said link and one end of said lever, and means for reversing said motions separately, substantially as described.

3. In a valve motion, the combination of the valve and its stem, a lever pivotally connected to said stem, a main link motion therefor, including a connecting rod, one end of which is pivoted to one end of said lever, a main connecting rod and connections between said last named rod and said first named connecting rod, an auxiliary link motion, including an eccentric, a rod operated by said eccentric, a link operated by said rod and connections between said link and said lever, and means for reversing each of said link motions separately, substantially as described.

In testimony whereof, I affix my signature, 50 in presence of two witnesses:

THOMAS WILSON
